UNITED STATES PATENT OFFICE.

WILLIAM D. FERRIS, OF STERLING, ILLINOIS, ASSIGNOR TO FRANTZ MANUFACTURING CO., OF STERLING, ILLINOIS, A CORPORATION OF ILLINOIS.

DOOR LATCH.

Application filed March 26, 1926. Serial No. 97,570.

This invention relates to door latches of that kind in which the door is provided at each side with a handle, and in which movement of the handle, when it is grasped to pull or push the door open, is operative to automatically unlatch the door, so that the door is unlatched and opened by one and the same handle, without the necessity of using the thumb piece ordinarily provided for lifting the latch.

This invention is in the nature of an improvement on the construction shown and described and claimed in application No. 84,316, filed January 28, 1926.

Generally stated, the object of the invention is to provide a novel and improved construction whereby the latch is lifted by upward movement of the handle at either side of the door, when the handle is grasped to either pull or push the door open.

It is also an object to provide certain details and features of construction, and combinations tending to increase the general efficiency and the desirability of a door latch of this particular character.

To these and other useful ends, the invention consists in the matters hereinafter set forth and claimed, and shown in the accompanying drawings, in which,—

Fig. 1 is a front elevation of a door latch embodying the principles of the invention, showing adjacent portions of the door and the door frame.

Fig. 2 is a vertical section on line 2—2 in Fig. 1.

Fig. 3 is a horizontal section on line 3—3 in Fig. 2.

Figs. 4 and 5 are detail views of the plates which are secured to the door and the door frame to co-operate with the latch bar.

As thus illustrated, the invention comprises a latch bar 1, which is pivoted at 2 on the bracket plate 3, the latter being secured by screws 4 to one side of the door.

This latch bar is adapted to strike the bevel 5 of the strike piece 6, and to then drop into the notch 7 of said strike piece, which latter is secured by screws to the door frame 8, or to a stationary portion of the building.

A plate 9 is secured to the edge of the door, and is provided with a guide slot 10 for said latch bar. These plates have holes 11 and 12 to receive a padlock, so that the door can be locked in closed position.

The mechanism for lifting the latch bar 55 comprises a handle 12, which is formed at its upper end with a shoulder 13 to engage the lower edge of the latch bar. The lower end of said handle is provided with a vertical slot 14, and a screw 15 is inserted 60 through this slot and through the guide plate 16, which covers the lower end portion of the handle, whereby the handle may be moved up and down on the door. A handle 17 is provided at the other side of the door, 65 and the two handles are connected together by a screw or bolt 18, or by any suitable means, and the lower end of the handle 17 is held by a guide plate 19 and a screw 20 extending through a slot in the handle 17, 70 whereby the lower ends of the two handles are alike, and both handles are slideable up and down on the door. Plates 21 and 22 are secured to opposite sides of the door, these plates having slots in which the screw or bolt 75 18 is movable up and down.

With this arrangement, either handle can be grasped to open the door, and by slightly raising the handle the latch bar is lifted out of engagement with the notch 7, thereby to unlatch the door 23, on which the handles and latch bar are mounted. Thus one and the same handle is sufficient to open or close the door and to lift the latch bar, so that the necessity of using the ordinary thumb piece 85 to lift the latch is entirely obviated, the two handles alone being sufficient for the purpose.

Without disclaiming anything and without prejudice to any novelty disclosed, what I claim as my invention is:

1. A latch mechanism comprising a latch bar, a strike piece for engaging said latch bar, to hold a swinging door in closed position, a handle movably mounted on the door, the handle being supported by means permitting up and down sliding movement of the handle relative to the door, said handle adapted for use in opening and closing the door, and means operated by said upward movement of the handle to automatically lift the latch when the door is opened, said bar being freely movable up and down independently of said handle, when the bar engages said strike piece.

2. A structure as specified in claim 1, in combination with another handle movable up and down on the other side of the door,

the two handles being connected together immediately below said means for lifting the latch.

3. A structure as specified in claim 1, said handle being provided with a vertically disposed slot at its lower end, and having a screw extending through said slot, providing a vertically sliding connection between the door and the lower end of the handle.

4. A structure as specified in claim 1, said handle being held against movement toward or away from the door, so that the handle

is only movable in a plane parallel with the door, and means on the upper end of the handle to engage said bar. ¹⁵

5. A structure as specified in claim 1, and another handle at the other side of the door, similarly mounted to slide up and down on the door, the door having a hole therein, and means extending through said hole to connect the two handles together, whereby the lifting of one handle will lift the other. ²⁰

WILLIAM D. FERRIS.
